UNITED STATES PATENT OFFICE.

ALBERT M. RUTTER, OF BALTIMORE, MARYLAND, ASSIGNOR TO HOLLOW BALL COMPANY, INCORPORATED, OF BALTIMORE, MARYLAND, A CORPORATION OF MARYLAND.

MACHINE FOR MAKING HOLLOW METAL BALLS.

Application filed November 26, 1924, Serial No. 752,320. Renewed September 28, 1928.

This invention relates to the manufacture of hollow metal balls, and more particularly to an improved machine for making such balls by rolling and spinning metal shells 5 having an opening or openings therein to close the opening or openings and round the shells.

In U. S. Patents Nos. 1,278,914 and 1,278,915 and pending application Serial No. 10 505,003, there is disclosed a method of making hollow metal balls which comprises in general forming an approximately spherical shell from a flat metal blank, or from a tube, by a series of forming operations, and then 15 rolling and spinning the shell thus formed under pressure in relatively movable, cooperating circular grooves in the faces of opposed discs or plates to close the hole or holes in the shell and improve its sphericity. The 20 machines illustrated and described in those patents and that application comprise a pair of horizontal plates, each having a single closing groove designed to cooperate with the single groove in the face of the other plate, and mounted for relative movement both rotational and axial, the lower plate being rotatable but fixed axially, and the upper being movable axially but keyed against rotation. The machine illustrated in the 25 30 35 patents differs from the one shown in the application primarily in the meridional section of the grooves, the latter being so shaped as to permit of a two-point contact with the shell below the mouth of the groove, this form of groove materially increasing the efficiency of the closing.

In operating a machine of this type the plates are separated and the balls to be closed placed by hand within the groove in the bottom plate. The upper plate is then lowered into contact with the balls and the lower plate rotated. The closing is effected by slowly lowering the upper plate thereby increasing the pressure on the balls. In order 40 45 50 to permit the balls to rearrange themselves within the grooves from time to time and thus insure a perfect distribution of the pressure and the production of a well-balanced ball, the pressure between the plates is periodically released and reapplied. A gauge is employed to indicate when the balls have reached a predetermined size, and when this point is reached the operator stops the machine, separates the discs and examines the

balls. If they are satisfactory the lower 55 groove is emptied and refilled; if not, the plates are brought together again and the rolling continued.

It is broadly the object of the present invention to improve upon these prior machines. Among the more specific objects are the provision of means for automatically feeding balls to and discharging them from the rolling plates, for permitting examination of the balls during the rolling and closing without interfering with the operation of the machine, and for permitting the balls to change their positions automatically during the closing operation without releasing the pressure between the plates. 70

In attaining these objects I remove a section of the non-rotatable plate and insert a guide block therein through which the balls are fed to the grooves, and through which they are discharged, all while the machine is 75 in operation. I also provide a common feed hopper or magazine for the balls, from which they are fed to the grooves and to which they are returned, thus forcing them to make the circuit time and again until their openings 80 have been closed and their diameters reduced to the desired size. As the balls emerge from the plates and into the hopper they may be removed and examined without interfering 85 in any way with the continuous operation of the machine. This passing through the hopper also results in a rearrangement of the balls so that their positions relative to the grooves vary continually and there is no necessity for a partial separation of the plates 90 to attain this end. The charging of such a machine is simply a matter of placing the balls in the feed hopper with the plates in position and starting the rotation. The discharge may be made equally simple. By making the axis of the plates horizontal so that the rotation is in a vertical plane and placing a discharge hopper below them, the machine may be instantly emptied at any time by a mere separation of the plates. 100

As a further improvement over the prior machines I also provide the rolling and closing plates for the smaller balls with a plurality of concentric closing grooves instead of the single pair shown in the machines of the patents and pending application, thus greatly increasing the capacity of the machine. When such plates are used I employ 105

a guide block which not only guides the balls to and from the grooves but which passes them from groove to groove in succession. Thus, all of the balls are passed around all 5 of the grooves and are given identical treatment.

In order that the invention may be more clearly understood I have illustrated a preferred embodiment of it in the accompanying 10 drawings in which Figure 1 is a vertical longitudinal section through a ball rolling and sizing machine constructed in accordance with the present invention, illustrating the relation of the ball-rolling plates during the 15 closing and sizing operation, and showing in detail the means for moving the non-rotatable plate axially and the manner in which the other plate is mounted for rotation, Figure 2 is a plan view of this machine showing the 20 means for rotating the rotatable plate and also the feed hopper and the conduits for leading the balls to and from the grooves in the non-rotatable plate, Figure 3 is a transverse section taken along line 3—3 of Figure 25 2 showing means within the hopper for constantly directing the balls into the feed conduit and also the means for operating these directing means, Figure 4 is an end elevation of the machine, with the operating hand-wheel removed, looking in the same direction as Figure 3, Figure 5 is an elevation of the face of the non-rotatable plate showing the 30 guide block in position, Figure 6 is a side elevation of the plates, taken partly in section along line 6—6 of Figure 5, and showing the passageways in the guide block through which the balls are fed to and from the grooves, and from one pair of cooperating 35 grooves to the pair next adjacent, Figure 7 40 is a sectional detail similar to Figure 6 but taken along line 7—7 of Figure 5, and Figure 8 is a detail showing the approximate meridional shape of the grooves and the position taken by a ball during the rolling operation.

In describing the machine illustrated in these drawings I shall first describe the rolling plates themselves and the manner in which they are mounted and moved. I shall then describe the feed mechanism, explaining how the balls are fed to and from the grooves and circulated therethrough. I shall then review briefly the entire operation of the machine.

The illustrated machine is equipped with two rolling, closing and sizing plates, 1 and 2, 55 each provided with four concentric ball-receiving grooves 3, each groove designed to cooperate with the corresponding groove on the other plate to form a single passageway or pair of grooves. These grooves are machined with outwardly diverging side walls designed to contact with the balls at two points below the mouth of the groove. They are in fact of substantially the same meridional section as those grooves illustrated and described in pending application No. 505,083. These 60 65

plates 1 and 2 are annular in form and are mounted within and supported by head castings 4 and 5 respectively.

Plate 1 is the rotatable plate. Thus head casting 4 is mounted for rotation about a 70 hollow journal 6 supported within the frame 7 of the machine and provided with suitable roller bearings 8 and thrust bearings 9. A plate 11 is mounted on the inner end of the journal to prevent outward axial movement 75 of the head casting 4. Rotation is effected through a gear 12 affixed to the head casting, meshing with a pinion 13 on a shaft 14, which is thrown into and out of driving relation with a constantly rotating pulley 15 by means 80 of a clutch 16 operated by a clutch lever 17. The rate of rotation of the pulley 15 and the gear ratio of the pinion 13 and gear 12 are such that the plate 1, which in this case is about eighteen inches in diameter, rotates at 85 about 150 R. P. M.

The head 5, which supports the non-rotatable plate 2, is carried by a ram 18 mounted for longitudinal sliding movement within a bearing 19 in the frame of the machine, and held against rotation by means of a key 21. Axial movement of this ram 18 and the plate 2 is effected through rotation of a shaft 22 making threaded engagement with the ram and having affixed to its outer end a gear 23 90 meshing with a pinion 24 on shaft 25 of a hand-wheel 26. The shafts 22 and 25 are journaled within castings 27 bolted to the right hand end of the machine frame. The outer face of the gear 23 is provided with a 95 scale 20, which cooperates with a pointer 28 secured to the lower face of the outer casting 27, to indicate the axial position of the plate 2 relative to the plate 1.

It is important that the grooves in the two 105 plates correspond exactly throughout all stages of the closing and sizing operation, and therefore the two plates must always be coaxial. In order to insure this relationship I have provided a pilot 29 affixed at one end to 110 the journal 6, and extending through a collar 31 affixed to the inner end of the journal and into a bushing 32 within the ram 18. This pilot is of sufficient rigidity and length to insure perfect axial alignment of the two plates 115 at all times.

I shall now describe the means for feeding the balls to the grooves in the plates, circulating them from groove to groove, and removing them therefrom. The non-rotatable 120 plate 2, as shown most clearly in Figure 5, is provided at one side with a cut-away section 33 into which is inserted a guide block 34. The operative face of this guide block 34 is provided with a series of obliquely cut passageways 35 cut on such an angle as to direct the balls from an inner groove to the next adjacent outer groove. The upper and inner portion of this block is provided with a transfer plate 36 having a series of rounded exten- 125 130

sions or fingers 37 which project beyond the face of the non-rotatable plate and into the grooves of the rotatable plate. This transfer plate is also provided with a series of passageways 38, one for each extension 37, which lead to and are in alignment with the passageways 35 in the block 34. The completed passageways 35-38, as shown most clearly in Figure 6, are curved in vertical section in order that the balls may pass without hinderance from one groove to the next. As the machining of such grooved passageways in a solid block would be an extremely difficult matter, I prefer to mill the passageways 35 as open cuts and close them by means of a curved cover plate 39. The block is also provided with a downwardly extending passageway 41 which leads to the innermost groove, and a horizontal passageway 42 leading from the outer groove and through the transfer plate and the block.

The balls are fed through block 34 and to the grooves from a hopper 43 supported on brackets from the frame of the machine, as shown most clearly in Figures 2, 3 and 4. The balls leave this hopper through a discharge orifice 44 located in its bottom, and proceed thence through a flexible feed conduit 45 to the passageway 41 in the block 42. The hopper 43 is inclined away from the machine at a slight angle, as shown in Figures 3 and 4, and the discharge orifice 44 is positioned at the highest point in the hopper bottom, for a reason which will be explained in a moment. The balls are returned from the grooves through passageway 42 in the guide block through a flexible return conduit 46 which enters the hopper 43 through its side. These conduits 45 and 46 are made flexible in order to permit movement of the plate 2 while the hopper 43 remains stationary. They are made of coil springs of the proper size. In order to insure a continuous flow of balls into the discharge orifice 44 I have provided within the hopper a constantly rotating agitator 47. This agitator comprises a circular disc 48 having a series of upstanding pins 49 situated around its periphery, each pin carrying an outwardly and downwardly extending arm 51. These arms 51 push the balls ahead of them around the annular track between the wall of the hopper and the periphery of the disc 48, and into the discharge orifice 44. They are made of flexible spring material so that if the balls become jammed the arms may yield and thus prevent any forcing or crowding of the balls into the orifice 44. The reason for inclining the hopper will now be apparent. The balls are moved up to the orifice 44 in a single line and are not interfered with by the other balls in the hopper. The agitator is constantly rotated through spindle 52 secured to the plate 47, friction disc 53, friction pulley 54, shaft 55, sheave 56,

belt 57, pulley 58, bevel pinion 59 and bevel pinion 61 mounted on shaft 14.

After the rolling operation is complete, the balls are discharged from the grooves through a funnel 62 and into a receptacle 63 slidably mounted upon the base 65 of the machine.

The machine operates as follows: The plate 2 is first moved by rotation of the hand-wheel 26 into a position closely adjacent plate 1, and the hollow metal balls to be rolled, closed and sized placed within the hopper 43. These balls have been previously shaped in stationary forming dies, and although approximately spherical are relatively unfinished, are oversize and have an opening or openings in them (depending upon whether they have been made from flat or tubular blanks.) The operator then shifts the clutch lever 17, applying the power to rotate the plate 1 and the agitator within the hopper. The balls are thus fed through the conduit 45 and passageway 41 in the guide block to the inner pair of cooperating grooves. Here they are subjected to a gyrating and spinning action and rapidly carried around the circuit of the inner groove. Arriving at the end of this groove the balls encounter the first finger 37 and are thus forced to leave the groove and pass through passageways 38-35 into the second groove. Here the rolling and spinning action is repeated, and the balls, after making the circuit of this second groove, are transferred to the next outer groove, and so on. When a complete circuit of all four grooves has been made, the last finger 37 directs the balls through passageway 42 into conduit 46 and back into the hopper. The flexible arms 51 of the agitator then direct the ball to the orifice 44, and it again passes through the cycle just described.

It will be observed that as the peripheral speed of any groove is greater than that of a groove of lesser diameter, the balls are moving at increasing speeds as they pass from the innermost to the outermost groove. This results in a slight separation of the balls as they proceed through the grooves and effectively prevents any crowding and interference within the grooves.

As the rolling and closing operation proceeds and the balls are reduced in size, the operator slowly turns the hand-wheel 26 to move ram 18 and the plate 2 toward the rotary plate. This action is continued until the balls, as they are discharged into the hopper from the conduit 46, are completely closed and properly sized. This condition will also be roughly indicated by the scale 20 and pointer 28. When this point is reached the machine is stopped, the plate 2 withdrawn and the balls allowed to fall by gravity through the funnel 62 and into the receptacle 63. The operation can, of course, be made

wholly continuous by diverting the closed and sized balls from the hopper and refilling the hopper when empty with a new batch of rough shells.

5. Balls of practically all malleable metals procurable in strip or tube form can be closed and sized in this machine. I have had satisfactory results with copper, Monel metal, aluminum, steel and stainless steel.

10. One of the chief advantages derived from the use of a machine such as the one just described is the considerable increase in output per unit time with a given power consumption over the output possible in the wholly intermittent type of machine. This increased efficiency results because of the continuous nature of the operation, because the balls can be examined without interfering with the operation of the machine, because they can 15 re-position themselves without a release of the pressure between the plates, and because, for the smaller sizes, a plurality of grooves are employed.

I claim:

25. 1. Apparatus for rolling and sizing hollow metal balls comprising the combination of two relatively rotatable plates having co-operating ball-receiving grooves, means for feeding balls to and discharging them from the grooves during the relative rotation of the plates, and a hopper from which the balls are fed to the grooves and to which they are returned by the rotation of the plates, means for feeding the balls from the hopper 30 to the grooves and means for returning the balls from the grooves to the hopper.

40. 2. Apparatus for rolling and sizing hollow metal balls comprising the combination of two relatively rotatable plates having a plurality of concentric cooperating ball-receiving grooves, and means for passing the balls from the inner to the outer grooves successively and back again to the inner during the relative rotation of the plates.

45. 3. Apparatus for rolling and sizing hollow metal balls comprising the combination of two relatively rotatable plates having a plurality of concentric cooperating ball-receiving grooves, means for passing the balls from the inner to the outer grooves successively during the relative rotation of the plates, a hopper, means for feeding the balls from the hopper to the inner grooves and means for returning the balls from the outer grooves 50 to the hopper.

60. 4. Apparatus for rolling and sizing hollow metal balls comprising the combination of two relatively rotatable plates having co-operating ball-receiving grooves, means for feeding balls to and discharging them from the grooves during the relative rotation of the plates, a hopper from which the balls are fed to the grooves and to which they are returned, a feed conduit leading from the hopper to 65 the grooves, a return conduit leading from the

grooves to the hopper and means within the hopper for moving the balls to the feed conduit.

5. Apparatus for rolling and sizing hollow metal balls comprising the combination of two relatively rotatable plates having co-operating ball-receiving grooves, means for feeding balls to and discharging them from the grooves during the relative rotation of the plates, a hopper from which the balls are fed to the grooves and to which they are returned, a feed conduit leading from the hopper to the grooves, a return conduit leading from the grooves to the hopper and constantly rotating means within the hopper for 70 moving the balls to the feed conduit.

6. In a machine for rolling and sizing hollow metal balls, the combination of a rotatable, axially fixed plate having an annular groove in its face, a non-rotatable axially movable plate having an annular groove in its face cooperating with the groove in the rotatable plate, a passageway in the non-rotatable plate through which balls are fed to the grooves, a second passageway in the non-rotatable plate through which balls are ejected from the grooves, a feed hopper for the balls and conduits connecting the passageways in the plate with the hopper.

7. In a machine for rolling and sizing hollow metal balls, the combination of a rotatable, axially-fixed plate having an annular groove in its face, a non-rotatable axially movable plate having an annular groove in its face cooperating with the groove in the rotatable plate, a passageway in the non-rotatable plate through which balls are fed to the grooves, a second passageway in the non-rotatable plate through which balls are ejected from the grooves, a fixed feed hopper for the balls and flexible conduits connecting the passageways in the plate with the hopper.

8. In a machine for rolling and sizing hollow metal balls, the combination of two plates having a plurality of concentric cooperating ball-receiving grooves, one of said plates being rotatable and the other non-rotatable, and a guide block inserted within the non-rotatable plate having passageways for leading balls from one groove to the one next adjacent.

9. In a machine for rolling and sizing hollow metal balls, the combination of two plates having a plurality of concentric cooperating ball-receiving grooves, one of said plates being rotatable and the other non-rotatable, a guide block inserted within the non-rotatable plate having passageways for leading balls from one groove to the one next adjacent, and extensions projecting into the grooves in the rotatable plate to direct the balls into 125 the passageways in the block.

10. In a machine for rolling and sizing hollow metal balls, the combination of two plates having a plurality of concentric cooperating ball-receiving grooves, one of said plates be-

ing rotatable and the other non-rotatable, a guide block inserted within the non-rotatable plate having passageways for leading the balls from one cooperating pair of grooves to the next adjacent outer pair, a feed passageway for leading the balls to the inner pair of grooves and a discharge passageway for leading the balls from the outer pair.

11. In a machine for rolling and sizing hollow metal balls, the combination of two plates having a plurality of concentric cooperating ball-receiving grooves, one of said plates being rotatable and the other non-rotatable, a guide block inserted within the non-rotatable plate having passageways for leading the balls from one cooperating pair of grooves to the next adjacent outer pair, a feed passageway for leading the balls to the inner pair of grooves, and a discharge passageway for leading the balls from the outer pair, and a common feed hopper with which both the feed and discharge passageways are connected.

12. In a machine for rolling and sizing hollow metal balls, the combination of two plates having a plurality of concentric cooperating ball-receiving grooves, one of said plates being rotatable and the other non-rotatable, a guide block in the non-rotatable plate having a series of oblique passageways each connecting adjacent grooves, and a transfer plate on said block having extensions projecting into the grooves in the rotatable plate to guide the balls through one pair of grooves to an adjacent pair through the passageways in the block.

13. In a machine for rolling and sizing hollow metal balls, the combination of two plates each having a plurality of concentric ball-receiving grooves designed to cooperate with similar grooves in the other plate, one of said plates being rotatable and the other non-rotatable, a guide block in the non-rotatable plate having a series of oblique open passageways each connecting adjacent grooves, a transfer plate on said block having extensions projecting into the grooves in the rotatable plate to guide the balls from one pair of grooves to an adjacent pair through the passageways in the block, and a plate closing the outer and open side of the passageways.

14. In a machine for rolling and sizing hollow metal balls, the combination of rotatable and non-rotatable plates having cooperating ball-receiving grooves, a feed hopper for the balls, a feed conduit extending from the hopper to the grooves, a return conduit extending from the grooves to the hopper, and flexible arms within the hopper for directing the balls into the feed conduit.

15. In a machine for rolling and sizing hollow metal balls, the combination of rotatable and non-rotatable plates having cooperating ball-receiving grooves, a feed hopper for the balls, a feed conduit extending from the hopper to the grooves, a return conduit extending

from the grooves to the hopper, a rotatable disc on the bottom of the hopper, upstanding pins around the periphery of the disc and flexible arms secured to the pins for directing the balls into the feed conduit.

16. In a machine for rolling and sizing hollow metal balls, the combination of rotatable and non-rotatable plates having cooperating ball-receiving grooves, a feed hopper for the balls, having an inclined bottom, a discharge orifice in the bottom of the hopper located at its highest point, a feed conduit leading from the discharge orifice to the grooves, and means within the hopper for directing the balls into the discharge orifice.

17. Apparatus for rolling and sizing hollow metal balls comprising the combination of a plate having in its face a plurality of concentric circular grooves having outwardly diverging side walls designed to make a two-point contact with the balls below the mouth of the groove, means cooperating with said plate to roll the balls within the grooves under pressure, and means for passing the balls from groove to groove during the rolling and sizing operation.

18. Apparatus for rolling and sizing hollow metal balls, comprising the combination of two plates, one rotatable and the other non-rotatable, provided in their faces with cooperating ball-receiving circular grooves having outwardly diverging side walls, each groove designed to make a two-point contact with the ball below the mouth of the groove, means for rotating the rotatable plate, means for exerting pressure between said plates to compress the balls, and means for continuously feeding the balls through the non-rotatable plate to the grooves and discharging them therefrom during the rolling and sizing operation.

19. Apparatus for rolling and sizing hollow metal balls comprising the combination of two plates, one rotatable and one non-rotatable, provided in their faces with a plurality of concentric cooperating ball-receiving grooves having outwardly diverging side walls, each groove designed to make a two-point contact with the ball below the mouth of the groove, means for rotating the rotatable plate, means for exerting pressure between said plates to compress the balls, means for feeding balls to the innermost groove, means for passing the balls from the innermost groove to the outermost groove successively, and means for discharging them from the outermost groove, all during the rolling and sizing operation.

20. A machine for closing apertures in hollow balls consisting of two symmetrically disposed parallel plates facing each other, designed to hold between them the hollow balls, each of the plates being provided with a series of concentric circular grooves, these grooves having a meridional section the bot-

tom of which is of a radius less than the radius of the ball at the beginning of the operation, means for feeding, discharging and circulating the balls from one groove to the other, means for exerting a variable pressure on the balls by drawing the two plates together, means for imparting a constant or

variable relative rotary motion to the plates with a view of giving the balls a combined rolling, spinning and gyrating movement to force successively all points of the ball surface into contact with the grooves.

In testimony whereof I affix my signature.

ALBERT M. RUTTER.
